UNITED STATES PATENT OFFICE.

HANS J. BENTSON, OF WINTHROP HARBOR, ILLINOIS, ASSIGNOR TO FREDERICK C. AUSTIN, OF CHICAGO, ILLINOIS.

EXCAVATING-MACHINE.

1,283,460.

Specification of Letters Patent.

Patented Nov. 5, 1918.

Application filed November 21, 1917. Serial No. 203,104.

To all whom it may concern:

Be it known that I, HANS J. BENTSON, a citizen of the United States of America, and resident of Winthrop Harbor, county of Lake, and State of Illinois, have invented a certain new and useful Improvement in Excavating-Machines, of which the following is a specification.

This invention relates to excavating machines for making ditches, and it relates more particularly to excavators of that kind in which digging apparatus is provided for forming the ditch along a line parallel with the direction of travel of the excavator, preferably at one side of the body of the excavator.

Generally stated, the object of this invention is to provide a novel and improved excavating machine of the foregoing general character.

A special object is to provide an improved construction and arrangement whereby a swinging scoop may be employed to advantage, in a novel and simple manner, as the means for digging the ditch, and whereby said scoop may be operated back and forth transversely of the line of travel of the excavator, and transversely of the ditch, so that the scoop will travel from one side of the ditch to the other, about an axis extending parallel with the direction of travel of the excavator, during the operation of digging the ditch.

It is also an object to provide certain details and features of construction and combinations tending to increase the general efficiency and desirability of an excavator of this particular construction.

To the foregoing and other useful ends, the invention consists in matters hereinafter set forth and claimed.

In the accompanying drawings:

Figure 1 is a side elevation of an excavator embodying the principles of this invention.

Fig. 2 is a rear elevation of said machine, showing the swinging scoop at work in the ditch.

Fig. 3 is a view similar to Fig. 2, but showing the scoop raised into dumping position.

Fig. 4 is a plan of said excavating machine.

As thus illustrated, my invention comprises a suitable body frame A mounted on front wheels B and a rear caterpillar C, or

other traction device, whereby the machine is adapted to travel forward over the surface of the ground. An engine D, of any suitable character, is arranged on the body for driving said caterpillar, and for operating the digging apparatus shown in the drawings and hereinafter described.

Said digging apparatus comprises a laterally extending boom E pivoted on the side of the body frame, at the rear end thereof, and provided at its outer end with a rotary wheel-like member F, the latter being pivoted at f to turn about a horizontal axis extending parallel with the direction of travel of the excavator. A brace e is provided for said boom, pivoted on the side of the frame A, and adapted to hold the boom against rearward or forward displacement. As shown, said wheel-like member F has four spokes 1, 2, 3 and 4, the spoke or arm 1 being provided at its end with a scoop G which swings back and forth transversely of the ditch. The other three spokes or arms of the wheel-like rotatable member F are provided at their ends with bearing portions g, which constitute the periphery of the wheel-like member, and which are adapted to engage the operating cables H and I, which cables have their ends secured to the scoop in any suitable or desired manner. The body frame A is provided with a longitudinally extending shaft J having thereon a drum j for the cable H, and a similar longitudinally disposed shaft K is provided with a drum k for the cable I, the latter being supported in elevated position at one point in the length thereof by the sheave L suitably mounted on an upright l secured to said body frame. With this arrangement, rotation of the drum j to wind up the cable H, while the drum k is rotated in the opposite direction to unwind the cable I, will result in forward movement of the scoop G from one side of the ditch to the other, thus causing said scoop to collect a load of dirt as it moves toward the body frame of the machine—that is to say, toward a point a little in rear of said body frame. On the other hand, rotation of the drum k in a direction to wind up the cable I, while the drum j is rotated in a direction to unwind the cable H, will result in backward movement of said scoop, so that it will be brought into position for another forward operation to take up another load. The frame A is also pro-

vised with a longitudinally extending shaft 5 upon which is mounted a pinion 6 to engage the rack 7 on the underside of the connecting rod M, the latter having its lower end pivoted at m to the outer end of the boom E, whereby rotation of said pinion in one direction will cause said rack to travel upwardly, thus causing the connecting rod M to pull the boom upward. Rollers 8, of any suitable character, are preferably arranged to engage the back of the connecting rod M, thereby to hold the rack in operative engagement with said pinion.

With this arrangement, after the scoop 15 G has been operated forward, the load taken up thereby is then dumped by raising the boom and the wheel-like member F into the position shown in Fig. 3, the cables H and I being manipulated at such time to bring 20 the scoop G into an up-side-down position over the bank N at one side of the ditch O, so that the load will be dumped immediately behind the caterpillar or traction device C previously described. The dumping devices, 25 whereby the bucket is caused to discharge its load, comprise a gate 9 hinged at 10 to the scoop, a locking bolt 11 mounted in guides 12 on said gate, together with a socket 13 on the scoop to be engaged by the end of 30 said locking bolt, and a cable or flexible connection 14 which connects the other end of said bolt with a fixed point on the end of the boom. With this arrangement, when the boom and the wheel-like member are 35 raised, and the wheel-like member rotated into the position shown in Fig. 3, the cable or flexible connection 14 is partially wound upon the drum 15; which latter forms the hub of said wheel-like member, so that in effect this connection 14 is shortened sufficiently to draw the bolt 11 out of the socket 13 at about the time the scoop reaches the dumping position, thus automatically unlocking the dumping gate 9 and permitting 40 the load to be discharged downward from the back end of the scoop onto the ground behind the excavator. The locking device, it will be understood, can be constructed so that the gate will slam shut when the scoop 45 is again lowered and brought around in the position shown in Fig. 2, as by beveling the end of the locking bolt, so that the gate will be automatically locked.

During the operation of the scoop, it will 55 be seen that the cable H exerts an advantageous pull to drag the scoop forward, inasmuch as the engaging portion g of the wheel-like member serves to keep this cable a given distance from the axis about which 60 said member rotates. In other words, the two cables H and I are partially wound upon said wheel-like member F, and when either cable is unwound, by the operation of its allotted winding drum, the cable exerts 65 a powerful pull on the scoop, because the

leverage through which either cable operates is always practically the same, being the radius of the wheel-like member, or approximately so, for all positions of the scoop.

It will be understood that any suitable means can be employed for connecting the shafts j and k with the engine D, previously described, or with any other suitable source of power, and that ordinary clutches, and 70 brakes of any suitable character, can be employed for controlling the operation of these shafts, and that no explanation or description of these devices is necessary. Also, any suitable arrangement can be employed 75 for transmitting power to the shaft 5 and for controlling the operation of this shaft so that the digging apparatus can be raised and lowered at will.

In practice, in view of the fact that the 85 caterpillar or traction device C is comparatively narrow, the weight of the digging apparatus is counter-balanced by a counter-balance weight, of any suitable character, not shown, mounted on the other side 90 of the frame. Also, if desired, an out-board wheel P can be provided on the land-side of the excavator, to bear upon the ground at any suitable distance from the caterpillar, thereby to steady the excavator or hold it in 95 position during the operation thereof. While the scoop G is in operation, the excavator is standing still. However, as soon as the scoop has worked long enough to reach the ultimate depth desired for the 100 ditch, the entire digging apparatus is then raised above the ground, and the caterpillar C is operated to move the machine forward, thereby to bring the digging apparatus directly over the position for the next downward cut in the ground. In this way, therefore, the ditch is formed in a step-by-step manner, by successive downward cuts of the swinging scoop. Obviously, the scoop can be operated to produce a ditch with sloping 110 sides, the ditch being formed by successive downward cuts of the rigging apparatus in the ground. In this way, the path of travel of the machine and the ditch are parallel, and the axis about which the digging apparatus operates is parallel with the ditch and with the line of travel of the excavator. 115

Any suitable means can be employed for limiting the upward swing of the boom E, when the dipper or scoop is raised into 120 dumping position. For example, a bumper 16, backed by a spring 17, in any suitable or desired manner, can be mounted on the upper portion of the frame A, near the rear end of the shaft 5, and this bumper will 125 limit the upward swing of the said boom. The wheel-like member F is, of course, on the rear side of the boom E, so that it swings upward in rear of the body frame A, and the different parts are all relatively ar- 130

ranged to permit this raising and lowering of the excavating apparatus, and so as not to interfere with each other during this raising operation.

5 With the foregoing construction, it will be seen that the scoop G is oscillatory about a horizontal axis which extends parallel with the ditch, and that the scoop is movable upwardly and laterally until it reaches a position directly in rear of the excavator body, and directly above the path of travel of the excavator. In other words, the scoop G fills by movement toward the body A, then rises and moves over the path of travel of the excavator, and then discharges its load. Also, 15 it will be seen that the scoop G passes the boom E, while the scoop is rising to the dumping position, and swings some distance away from the boom before reaching the dumping position. Thus the bucket moves upward toward the boom while loading and passes the boom while rising to the dumping position, thereby to discharge the load above the path of travel of the excavator, preferably on the ground in rear of the excavator body.

What I claim as my invention is:

1. In an excavating machine for making a ditch, the combination of a traveling body, 30 a rotatable member mounted to operate about a horizontal axis, means for supporting said member in position on said body, a scoop supported on said member to operate about said axis, instrumentalities for oscillating said member to swing said scoop back and forth in the ground so that the ditch will extend parallel with the direction of travel of said body, connections for raising and lowering said member, adapted to 35 operate with said instrumentalities to raise said scoop into dumping position directly behind said body, and devices for causing a discharge of the load from said scoop.

2. A structure as specified in claim 1, said 45 instrumentalities including (1) a flexible connection for pulling the scoop forward, (2) a flexible connection for pulling the scoop backward, and (3) means to operate said flexible connections to rotate said member first in one direction and then in the other; said member being wheel-like in form and having means at the periphery thereof to engage said connections so that first one connection and then the other is partially 55 wound around said member during the back and forth motion of said scoop.

3. A structure as specified in claim 1, said 60 instrumentalities including (1) a cable to pull the scoop forward, (2) a cable to pull the scoop backward, and (3) drums to operate said cables; said member being provided with radially extending arms to one of which said scoop is secured, and at the ends of which said other arms are provided with 65 means for engaging said cables during the

oscillatory motion of said member, and said devices including a dumping-gate at the rear end of said scoop.

4. A structure as specified in claim 1, said axis extending longitudinally of the ditch, 70 parallel with the direction of travel of said body, so that said scoop operates back and forth from one side of the said ditch to the other during the oscillation of said member.

5. A structure as specified in claim 2, said member being arranged so that said scoop swings back and forth from one side of said ditch to the other during the oscillatory movement of said member.

6. A structure as specified in claim 3, said 80 member being disposed laterally of said body, with said axis extending parallel with the direction of travel of said body along the ground at one side of said ditch, so that said scoop operates back and forth transversely of said ditch.

7. A structure as specified in claim 1, said member being disposed at the rear end of said body, with said axis extending parallel with the direction of travel of the machine, 90 so that said scoop operates transversely of the trench, whereby the ditch is formed by successive downward cuts in the ground, said body being movable forward after each cut is finished to bring said scoop above the position for the next downward cut in the ground.

8. In an excavating machine for making a ditch, the combination of a body movable along the top surface of the ground in a direction parallel with the ditch, a boom extending laterally of said body, a wheel-like member mounted on the outer end of said boom, whereby said member is rotatable about an axis parallel with the direction of 105 travel of the machine, a scoop carried or the periphery of said wheel-like member mechanism to raise and lower said boom, a cable extending under the periphery of said member to operate said scoop forward, a 110 cable extending over the periphery of said member to operate said scoop backward, drums for operating said cables, and devices for causing said scoop to discharge the load therefrom.

9. A structure as specified in claim 8, said devices being operable automatically by the rotation of said member.

10. A structure as specified in claim 8, 120 said devices including (1) a pivoted dumping-gate at the rear end of said scoop, (2) a locking device for said gate, (3) a connection extending from said locking device, and (4) means on said member to operate said connection to automatically open said gate 125 when said scoop reaches the dumping position or point of discharge.

11. A structure as specified in claim 8, 130 said boom and member being disposed in position at the rear end of said body, so that

- said body is always ahead of the excavation, and means at the side of said body to brace said boom against rearward displacement thereof.
5. 12. In an excavator for making a ditch, the combination of a body adapted to travel parallel with the ditch at one side thereof, a boom pivoted at the rear end of said body and disposed in position to extend transversely of the ditch, a scoop for digging the ditch and carrying the excavated dirt upward therefrom, means to pivotally mount the scoop on said boom, so that said scoop is movable back and forth transversely of the ditch about a horizontal axis extending longitudinally of the ditch, connections to oscillate said scoop about said axis, means to raise said boom, adapted to cooperate with said connections to raise said scoop into dumping position directly behind said body, mechanism on said body to operate said connections, and devices for causing said scoop to automatically discharge the load therefrom when the boom is in raised position.
13. In an excavator for making a ditch, the combination of a body equipped to travel parallel with the ditch at one side thereof, a scoop operable back and forth crosswise of the ditch, instrumentalities whereby the scoop enters the ground at one side of the ditch and is caused to take up a load by movement first downward and then upward toward the side of the ditch at which the excavator travels to give the ditch definite shape in cross section and whereby the scoop is then raised and brought into dumping position above the path of travel of the excavator body, and means for causing the scoop to discharge its load after reaching said dumping position.
14. A structure as specified in claim 13, said instrumentalities comprising a boom pivoted on the side of said body to overhang the ditch, an oscillatory member pivoted on the end of said boom to oscillate about said axis, said scoop being rigidly secured to said oscillatory member, flexible connections to oscillate said member to operate the scoop in the ditch and to assist in bringing the scoop into dumping position, and means to raise and lower said boom.
15. A structure as specified in claim 13, said instrumentalities including a laterally extending boom, means to raise and lower said boom, and an oscillatory member to which said scoop is secured and which is pivoted upon the end of said boom so that the scoop can pass the boom while rising to the dumping position.
- Signed by me at Chicago, Illinois, this 2d day of November, 1917.
- HANS J. BENTSON.
